UNITED STATES PATENT OFFICE.

HENRY VATTER, OF LAWRENCE, MASSACHUSETTS.

IMPROVEMENT IN RETURN-FLUE STOVE-PIPES.

Specification forming part of Letters Patent No. 77,684, dated May 5, 1868.

To all whom it may concern:

Be it known that I, HENRY VATTER, a native of Neustadt, in the Kingdom of Prussia, at present temporarily residing at Lawrence, in the county of Essex and State of Massachusetts, have invented certain new and useful Improvements in Return-Flue Stove-Pipes, of which the following is a full, clear, and exact description, reference being had to the accompanying drawings, making part of this specification, in which—

Figures 1 and 2 are vertical sections at right angles with each other; Fig. 3, a transverse section on the line A B of Fig. 1; Fig. 4, a bottom end view; Fig. 5, a side view of a return-flue pipe, to be used without elbows.

My invention and improvement in return-flue stove-pipes consist of a central partition, A, which is fitted and fastened to the inside of the round pipe, and extends from near the top downward to a little below the upper side of the outlet B, and in combination with such partition of a tongue-shaped damper, C, which is adjustable to allow the smoke and gases to pass directly from the stove to the flue of the chimney, or upward over the top of the partition, and downward on the opposite side thereof, and then through the outlet B to the chimney.

The object of this invention is to allow the stove to be set nearer the chimney and thereby economize in room, to save considerable heat in cold weather, or to allow the heat to pass off in warm weather, and all with a cheap and simple device.

In Fig. 1, D is the circular flange at or near the back corner of the stove, a portion, E, of which is also shown. The return-flue pipe is placed on the outside of the flange D. The outlet branch B being applied to the pipe at the proper height, enters the hole in the chimney. When the swing damper C is set as indicated by dotted line C', the smoke and gases pass nearly directly from the stove to the chimney, as shown by an arrow 1, and when the damper C is set as indicated, then the smoke and gases pass upward over the top of the partition A and downward on the opposite side thereof, and through the outlet B to the chimney, as

indicated by the arrows 2, thus accomplishing with a single stove-pipe without an elbow what has formerly been done with two parallel pipes and three elbows.

The return-flue pipe may be of any length desired, and still allow most of the heat to pass nearly direct to the chimney when not wanted in the room, by simply adjusting the damper C.

This last-named operation cannot be accomplished with the two parallel pipes, as all the gases and smoke pass through the whole length of such pipes and cannot be turned in another and more direct course.

The damper C swings on a rod, g, which passes through the pipe and is fastened to the top of the damper. The projecting end d of the rod is bent or turned over, as shown, and bears on a curved piece, e, on the pipes, to hold the damper when set.

My invention may be readily applied to a stove which has an outlet at the back instead of on the top, by means of a short elbow between such back outlet and the lower end of the return-flue pipe, or by a branch, b, similar to the outlet B, but at the opposite side of the pipe and a little more than its size lower down, as shown in Fig. 5, and then a movable stopple may be placed in the lower end of the pipe, as in the top end, and the inside of such pipe may then be cleaned without removing the pipe or disturbing the stove.

Only a limited draft can be produced where two vertical parallel pipes are employed, but in the use of my invention the draft can be increased or diminished or regulated at pleasure.

What I claim as new, and desire to secure by Letters Patent, is—

1. A return-flue stove-pipe, constructed and arranged for operation, as and for the purpose substantially as described.
2. The damper C, constructed as described, in combination with the partition A and the pipe, for the purpose and substantially as described.

HENRY VATTER.
